Int. Cl. D21—03

U.S. Cl. D34—5

FIG. 1 is a plan view of one face of a golfer's tool incorporating my new design;

FIG. 2 is a plan view of the golfer's tool of FIG. 1 showing a knife and turf repair instrument in an open position;

FIG. 3 is a plan view of the rear face of the golfer's tool of FIG. 1;

FIG. 4 is a side elevation view of the golfer's tool of FIG. 1, the opposite side being a mirror image thereof;

FIG. 5 is a top end view of the golfer's tool of FIG. 1; and

FIG. 6 is a bottom end view of the golfer's tool of FIG. 1.

The principal novelty of the design lies in the features which are common to the embodiments of FIGS. 1 and 3.

In another embodiment of this design both front and rear faces of the tool correspond to FIG. 3.

I claim:

The ornamental design for a golfer's tool or the like, substantially as shown and described.
